UNITED STATES PATENT OFFICE.

EDWARD E. CLEMENT, OF WASHINGTON, DISTRICT OF COLUMBIA, ASSIGNOR TO,
EDWARD F. COLLADAY, OF WASHINGTON, DISTRICT OF COLUMBIA.

RADIO BROADCAST DISTRIBUTING SYSTEM.

Application filed July 3, 1924. Serial No. 724,103.

My invention relates to systems of radio broadcast distribution and has for its object the organization of a system capable of giving service to subscribers in regional groups, which may be related to each other by a general organization corresponding to the long distance telephone organization, and is in the nature of an improvement or further development of the general type of system disclosed in my prior copending applications, Serial No. 699,023, filed March 13, 1924, and Serial No. 701,123, filed March 22, 1924, the latter patented January 6, 1925, as No. 1,522,362.

The object of the present invention is to provide a system of the above type which will afford the use of one or two audion tubes at the subscriber's station, for example, a detector and amplifier tube and permit the use of the subscriber's radio telephone receiving set simultaneously with the use of his main telephone set or an extension telephone set, while preventing substantially any reduction in the efficiency and strength of the radio set due to the extra draft of current from the line by the transmitter of the land telephone.

I attain the object of my invention by providing each subscriber with receiving radio telephone apparatus, and providing at the central office radio receiving and retransmitting apparatus capable of receiving from long distances in any well known or other suitable manner and relaying or transforming the signals received into suitable form for efficient transmission thereof over the line circuits of the various subscribers. To enable the subscriber to operate his radio set for reception of radio signals over either the wires or by pure radio during use of the telephone without detracting from the efficient operation of the radio telephone set due to the use of current by the telephone transmitter, I provide means for connecting the filament circuits of the one or two audion tubes at the subscriber's station in series with the telephone transmitter which I find can be arranged to add sufficient resistance to reduce the drop across the line at the subscriber's station without detracting from the quality of the telephone transmission, thus using the filaments to serve the double function of energizing the tubes and adding the necessary resistance to hold

the line potential sufficiently high to maintain the necessary plate voltage.

Other objects of my invention will be apparent from a perusal of the following specification and the drawings accompanying the same.

My invention is illustrated in the accompanying drawings, in which:

Fig. 1 is a diagram of a subscriber's substation apparatus.

Fig. 2 is a diagram of the telephone and radio telephone central office.

Fig. 3 is a diagram of a subscriber's simplified circuit using one tube.

Referring to the drawings in detail, and first to Figs. 1 and 2, the telephone circuits as shown in Fig. 1 are situated at the subscriber's substation and consist of the tip and sleeve, or plus and minus line wires 1 and 2 leading into the subscriber's station from the central office. Connected to the line wires 1—2 is the usual subscriber's telephone set T having the ringing condenser 3 and ringer 4 connected in series across the line through a radio choke coil 5, and a transmitter 6 arranged to be connected with the line in different circuit arrangements according to the use or non-use of the radio telephone as will be presently described. The subscriber's telephone set also contains the usual induction coil 7 arranged to have its primary winding connected in the circuit of the transmitter 6 through the switch-hook contacts 8 and has its secondary winding connected in the receiver circuit. The subscriber's radio telephone receiving set comprises a detector tube D having its grid-filament or input circuit connected to the moveable arms 13 and 14 of the radio service switch 15 which may take the form of any suitable double throw or two way gang switch having other blades or moveable arms 16 and 17 and an indicating arm 18 all on a common shaft 19. The lower stationary contacts 20 and 21 of this switch are connected across the terminals of the inductance 11 while the upper stationary contacts 22 and 22^a also cooperating with the switch arms 13 and 14 are connected across the inductance 23 the upper terminal of which inductance is connected to the tuning condenser 23^a to the plus line conductor 1. The switch arm 16 is connected through conductor 24 to the

minus line conductor 2 while its middle or off contact 25 is connected through conductor 26 to the series return conductor 27 which leads to the plus line conductor 1 through the transmitter 6, switchhook contacts 8, winding of induction coil 7, branch conductor 28 and radio choke coil 5. The upper and lower contacts of the switch 16 are not wired. The central contact on 10 which the switch arm 17 normally rests in the off position is not wired but the two extreme or upper and lower contacts 29 and 30 are connected together through conductors 31 and 32 of the middle arm 33 of 15 the telephone switch 34. The radio service switch 15 has thus three switching positions as indicated by the legends for the indicator arm 18, namely, "Off", "Local", and "Long distance", for purposes which will later be 20 described herein. The telephone switch 34 is also a three-positioned gang switch having an indicator arm 35 and two switching arms 33-36 movable in unison therewith. The switching arm 33 is directly connected 25 with the conductor 31 while the switching arm 36 is connected through conductor 37 and resistance 38 to the conductor 31. The telephone switch has three positions as indicated by the legends associated with the 30 indicating arm 35, namely, "Radio", "Radio with extension phone", and "Radio with main phone". The switch arm 33 is arranged to connect the conductors 31-32 with the plus telephone line 1 through a 35 suitable resistance such as the lamp 39 only in the middle or radio position of the telephone switch 34, while the switch arm 36 is arranged through its stationary contacts 41 and 42, to connect the wire 37 with the 40 series return wire 27 or the transmitter circuit 43 of the extension telephone EX, which transmitter circuit is inductively coupled in the usual manner through the windings of the induction coil 44 to the telephone receiver 45. It will thus be seen that 45 with the radio service switch in the position shown in the drawing, the off position, the radio telephone set will be disconnected and incapable of use because the input circuit of the detector tube D terminating in the 50 switch arms 13-14 is open at such switch arms, and the transmitter 6 of the subscriber's land telephone set T is connected to the minus line wire 2 through the series 55 return conductor 27, conductor 26, switch contact 25, switch arm 16, and a conductor 24. Under this condition the subscriber's land telephone T is connected to the line in the usual manner except for the insertion of 60 the radio choke coil 5. The subscriber's set is also provided with an amplifier tube A coupled in the usual manner through a radio transformer 46, a detector jack 47 to the plate circuit conductor 48 which leads 65 through a feed back coil 49 to the plate of

the detector tube D. The output or plate circuit of the amplifier A is connected across the line wires 1-2 with a single stage 70 amplifier jack 50 in series for the insertion in said output circuit of a suitable receiving device which may be a loud speaker as indicated at 51.

The subscriber's line wires 1-2, extend to the telephone exchange system shown in Fig. 2 where they terminate in the usual 75 telephone exchange terminal apparatus indicated symbolically by the line jack 52. Where the line is unusually short, suitable balancing resistances may be inserted as indicated at 53. Other lines terminate at the 80 exchange such as the line 201-202 terminating in the line jack 54. At the central station is provided a plurality of the operator's interconnecting cord circuits one of which is here shown and consists of the 85 usual answering and calling plugs 55 and 56 respectively, with the usual listening key 58, ringing key 57, common battery supply 59, repeating coil 60 and talking condensers 61 and 62, connecting and operating in the 90 usual manner as well understood in the art and which will be more clearly brought out in the description of operation to follow. In addition to the usual common battery 95 59, the operator's cord circuit is provided with a booster battery 63 arranged to be thrown in series with the battery 59 by means of the double pole double throw switch arms 64 and 65 cooperating with the contacts 66-67 and 68-69, respectively. The central office is also provided with a 100 suitable radio relaying or transmitting apparatus 70 having its output conductors 71-72 arranged to be connected through switch 73, to conductors 74-75 constituting 105 a radio bus to which a subscriber's line may be connected through a radio jack 76.

In the operation of the system shown in Figs. 1 and 2, using the 2-tube subscriber's 110 radio receiving set, and with the various switches at the subscriber's station in the position shown in Fig. 1, the subscriber may close his telephone line 1-2 through his transmitter 6 for signalling the central office by raising his receiver 108 in the usual 115 manner. The circuit of the transmitter 6 across the telephone line may be traced from line wire 1, through radio choke coil 5, conductor 28, winding of induction coil 7, switchhook contacts 8, transmitter 6, conductors 27, 26, 25, 16, 24, to line wire 2. This closure of the subscriber's line circuit signals the central office operator through the usual central office line signal not here 120 shown as they form no essential part of the present invention and may be of any known or other suitable form. With the subscriber's circuits and apparatus in the condition shown in Fig. 1 he may also be signalled from the central office in the usual 125 manner through the radio jack 76. The 130

manner by the application of a ringing current to his line wires 1-2 the circuit for which may be traced from line 1, through elements 5, 28, ringer 4, condenser 3, to line 5 wire 2.

When the subscriber desires radio service, he signals the central office operator in the usual manner, and the operator inserts her answering plug 55 in the subscriber's jack 52 and actuating her listening key 58 establishes communication with the calling subscriber through her cord circuit over the line in the usual manner and ascertaining the subscriber's wish for radio service inserts the plug 56 of the same cord circuit in the radio jack 76, and throws the switch arms 64-65 into engagement with the contacts 66-68. The subscriber's line is now supplied with battery current from the main battery 59 and booster battery 63 in series, the circuit of which battery supply may be traced from battery 59, through battery 63, repeating coil winding 80, cord conductor 81, cord conductor 82, tip contact of plug 56, tip contact of jack 52, subscriber's line conductor 83, line wire 1, to subscriber's station of Fig. 1, and back from subscriber's station by way of line conductor 2, conductor 84, sleeve of jack 52, sleeve of plug 30 55, cord conductor 85, cord conductor 86, winding 87 of repeat coil 60, conductor 88, and conductor 89 back to battery 59. Thus both batteries 59 and 60 are connected in series across the subscriber's line wires 1-2 35 for current supply to the subscriber's station the wire 1 being plus and the wire 2 being minus. As the batteries are each approximately of 25 volts the potential thus put upon the subscriber's line with the line circuit open is approximately 50 volts. The subscriber is 40 now able to receive either local broadcast over his antenna 9 or long distance broadcast relay from the central office over his line wire by moving the switch indicator arm 18 into either the local or long distance 45 position, respectively. If he desires local broadcast and moves the arm 18 down into the position indicated as local, the switch arms 13-14 will engage the contacts 20 and 21 or connect the input circuit of his detector 50 tube D with the antenna ground connection 9-12. This connection may be traced from antenna 9 through the wave length tuning condenser 10 and in parallel through the 55 inductance 11 to the ground 12 and from the upper terminal of the inductance 11 through contacts 20-13 to the grid of the detector tube D and from the filament through contacts 14-21 to the lower terminal inductance 11. The filaments of the subscriber's 60 detector tube B and amplifier tube A are energized in series by current from line wire 1 through resistance lamp 39, switch contact 40, switch arm 33, conductors 32 and 31, contacts 30 and 17, filament of tube 65

D, resistance element 90, filament of tube A to line wire 2. The resistance of the lamp filaments and the elements 39 and 90 is such as to permit the lamp filaments to be supplied with the proper amount of current, 70 which resistance is also sufficient to hold the line voltage at sufficient amount to supply the necessary working potential to the plate circuits of the tubes allowing for the drop in voltage due to the flow of current through 75 the line resistance. The plate circuit for the detector tube D may be traced from line wire 1 through contacts of jack 47, conductor 48, tickler coil 49, to the plate electrode of tube D and from thence by way of the filament through resistance element 90 and filament of tube A to the line wire 2. The plate circuit of the amplifier tube A may be traced from line wire 1 through jack 50 and loud speaker 51 to the plate 80 element of the tube A and from thence by way of the filament of tube A directly to the line wire 2. Thus the full potential of the line, allowing for the drop due to the flow of current through the filaments, is applied to the amplifier plate while the potential on the plate of the detector D is somewhat less than the line potential due to the flow of current through the resistance 9. This 85 gives the tubes proper different plate voltages 90 for efficient operation as detector and amplifier respectively. If desirable the subscriber may listen in on the output circuit of the detector tube only, by way of the first stage jack 47, by the use of the loud speaker 51 95 or the usual head set not shown.

When the subscriber desires to receive long distance matter relayed from the central office he moves the indicator arm 18 of the radio service switch up into the long 105 distance position which preserves the circuit of the tube filaments by moving the contact 17 into engagement with the contact 29, but disengages the switch arms 13-14, which form the terminals of the input circuit of the detector, from the contacts 20-21 and moves them into engagement with contacts 22-22^a which places the input circuit across the terminals of the long wave inductance 110 23. This position of the radio service switch also connects the inductance 23 in series with the tuning condenser 23^a across the line wires in a circuit which may be traced from line wire 1, through condenser 23^a, inductance 23, contacts 22^a-14, filament of tube D, resistance element 90, filament of tube A, to the line wire 2. The subscriber's radio receiving circuit is now in condition to receive the long 115 wire-guided waves supplied over his line circuit 1-2 from the central office relay transmitter 70. This relay transmitter may be of any known or other suitable form operable to receive signals from long distance and 120 lay the same as modulations on a long carrier wave distributed over the subscriber's line,

or it may take the form of any suitable source of long wave transmitter and modulator capable of distributing modulated long waves over the subscribers' lines. The path 5 of the long waves from the source 70 at the central office Fig. 2 to the subscriber's station Fig. 1 may be traced from the source 70, through elements 71, 73, 74, tip of radio jack 76, tip of calling plug 56, 82', 81', audio or 10 telephone condenser 62, tip of answering plug 55, tip of jack 52, 83, line wire 1, to Fig. 1, long wave tuning condenser 23^a, 22, 23, 22^a, 14, filament of tube D, 90, filament of tube A, back over line wire 2 to Fig. 2, 84, sleeve 15 of line jack 52, sleeve of answering plug 55, audio or telephone condenser 61, 86', 85', sleeve of calling plug 56, sleeve of radio jack 76, 75, 72, back to the source 70.

When the subscriber desires to use either 20 his extension telephone EX or the main telephone T, for the purpose of making a call or communicating with the central office or broadcast station without interrupting his radio service, he may do so by moving the 25 indicator arm 35 of his telephone service switch 34 to the position marked "Radio with ext. phone" or the position marked "Radio with main phone", as the case may be. With the indicator arm 35 in the left 30 hand position, the switch arm 33 is moved out of engagement with the contact 40 and the switch arm 36 is moved into engagement with the contact 42 thus opening the direct communication of the filament circuit with 35 line wire 1 through contact 40 and closing the filament circuit to line wire 1 through contacts 36—42 and the transmitter circuit 43 of the extension telephone which connection may be traced from line wire 1, through 40 elements 43, 42, 36, 37, 38, 31, contact 29 or 30 according to the position of the radio service switch 70, thence through the lamp filaments to line wire 2. As the transmitter circuit 43 of the subscriber's extension telephone EX is now bridged across the line he 45 may communicate with the central or broadcast station in the usual manner. When the indicator arm 35 of the telephone service switch is moved to the right hand position, the switch arm 33 is moved to the right out 50 of engagement with the contact 40 which opens the direct communication of the filament circuit to line as before, while the switch arm 36 is moved into engagement 55 with the contact 41 which connects the filament circuit across the line in series with the transmitter circuit of the main telephone T which circuit connection may be traced from line wire 1, through elements 5, 28, 7, 60 8, 6, 27, 41, 36, 37, 38, 31, contacts 29 or 31 according to the position of the radio service switch 17, filaments of tubes D and A, to line wire 2.

The subscriber is thus able to make use of 65 his telephone line for telephone purposes

without interfering with the use of his radio-telephone receiving set and by the provision of the extension phone in proximity to his radio telephone receiving set is enabled to establish immediate communication with the broadcasting station for the purpose of applause or the like without having to interrupt his radio reception. 70

The subscriber's simplified radio receiving set of Fig. 3 is identically the same as 75 that of Fig. 1 except that before one tube, the detector tube D is used, a telephone headset 151 is used instead of a loud speaker.

Having thus described my invention, what is claimed and desired to be secured by Let- 80 ters Patent is:

1. A radio telephone distributing system, comprising in combination with a common battery telephone exchange system, telephone apparatus at the subscribers' stations 85 operable on the normal telephone line voltage, radio receivers at the subscriber's stations having current consuming devices arranged to take current from the subscribers' lines and requiring a voltage higher than the normal telephone line voltage, a booster current source at the telephone central office and means to connect the same for increasing the potential on a given line 90 when its radio receiver is in service sufficiently to operate the said high voltage current consuming device associated with that line, and means for connecting a portion of the radio receiver in series with the said normal voltage telephone apparatus to protect 95 the latter against the increased potential. 100

2. The combination with a common battery telephone exchange system, having a normal or a low voltage transmitter at the subscribers' stations of a radio receiver at a 105 subscriber's station having a thermionic tube connected to the subscriber's telephone line for energization therefrom of its filament and plate circuits, said plate requiring a higher voltage than the normal voltage of 110 the line, means at the central office for boosting the line voltage on a given line when its radio receiver is in service to the voltage required to operate the said plate circuit, and resistance means arranged to be 115 connected in series with the filament of the thermionic tube and the normal voltage telephone transmitter of sufficient resistance to maintain the required current flow through the filament and protect the said normal voltage transmitter against the higher voltage. 120

3. The combination with a common battery telephone exchange system having main telephone sets at the subscribers' stations in which the transmitter circuit is connected in series with the subscriber's telephone line for operation, of a radio receiver at the subscriber's station having a triode tube, an extension telephone set associated with the subscriber's radio receiver and 125 130

switching means for connecting the filament of the triode tube in series with either the transmitter of the main telephone set or the transmitter of the extension telephone set.

5 4. The combination with a common battery telephone exchange system having main telephone sets at the subscribers' stations energized over the line, of a radio receiver and an extension telephone associated therewith at the subscriber's station and switching means for connecting the subscriber's radio receiver for energization in series with either said main telephone or said extension telephone.

15 5. The combination with a common battery telephone exchange system having main telephone sets at the subscribers' stations energized over the subscriber's line, of a radio receiver and an extension telephone set associated therewith at the subscriber's station, resistance means at the subscriber's station, said resistance means and each of said main telephone and extension telephone having substantially the same resistance, and switch-

ing means for connecting the energizing circuit of said radio receiver in series with either one of said resistance means, main telephone, or extension telephone, alone.

6. In a common battery telephone exchange system having telephone exchange system apparatus at the subscriber's station operable on the normal telephone line voltage, the combination of a triode audion tube situated at the subscriber's station and requiring for its plate circuit a voltage higher than the said normal voltage, means for increasing the voltage on a given line to that required by the plate circuit of the triode tube, said triode tube having its filament circuit arranged to be connected in series with said normal voltage telephone apparatus when the line voltage is increased to protect the telephone apparatus against increased voltage.

In testimony whereof I hereunto affix my signature.

EDWARD E. CLEMENT.
